UNITED STATES PATENT OFFICE.

MELVIN W. MOREHOUSE, OF BROOKLYN, NEW YORK, ASSIGNOR TO MERGENTHALER LINOTYPE COMPANY, A CORPORATION OF NEW YORK.

TYPOGRAPHICAL MACHINE.

1,129,892.

Specification of Letters Patent.

Patented Mar. 2, 1915.

Application filed March 20, 1913. Serial No. 735,595.

To all whom it may concern:

Be it known that I, MELVIN W. MOREHOUSE, a citizen of the United States, residing at Brooklyn, in the county of Kings and State of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to 15 form a slug or linotype against the matrices which produce the type characters thereon, and the matrices thereafter returned through a distributing mechanism to the magazine from which they started.

20 More particularly, it relates to machines of this kind when equipped with interchangeable magazines. In the employment of these interchangeable magazines, and particularly such as are not themselves provided with escapement devices, it becomes necessary to lock the matrices therein, so that they will not be displaced or spilled during the shifting of the magazine. This 25 result has been effected in various ways, such for instance as by the temporary insertion of a transverse bar which passes beneath the ears of the matrices, or by the provision of a rock shaft or rod, which when operatively turned similarly engages under 30 the matrix ears. In the present instance, I preferably form one of the magazine plates with a transversely movable section, which in one position permits the matrices to pass freely, and in another position locks them 35 securely against displacement. More specifically, this movable section is formed on its inner side with grooves, which normally register with the corresponding grooves in the main portion of the magazine, but are thrown out of registry therewith, when the section is adjusted transversely, so that the intermediate ribs aline with the magazine 40 grooves and prevent delivery of the matrices.

45 In the accompanying drawing, I have

shown my invention in preferred form and by way of example, and as applied to the specific style of machine referred to, but obviously many changes and variations may be made therein, and in its mode of application, which will still be comprised within its spirit. For instance, it may be adapted to other kinds of typographical machines, such as typesetters, typecasters, and the like, or machines which handle type or dies instead 60 of matrices.

Generally speaking, I desire it to be understood that I do not limit myself to any specific form or embodiment, except in so far as such limitations are specified in the 70 claims.

Referring to the drawings: Figure 1 is a vertical sectional view through the lower part of the magazine, with my improvements embodied therein; Fig. 2 is a section 75 on the line 2—2 of Fig. 1; Fig. 3 is a section on the line 3—3 of Fig. 2; and Fig. 4 is a similar section, but showing the parts in different position.

The replaceable magazine A for the matrices X is formed interiorly with the grooves A¹ to receive the matrix ears X¹, and is provided with the customary escapement devices B. It is to be noted that the escapements are separately supported, and consequently that when the magazine A is removed from the machine, additional means are necessary to prevent the displacement of the matrices therefrom. The parts so far described constitute in themselves no part 80 of my improvements, and are or may be substantially the same as those employed in the ordinary commercial form of linotype machine.

According to my present invention, I 95 form the lower portion of the upper magazine plate with a transversely adjustable section C, it being capable of a limited extent of movement with reference thereto, this being provided for in the present instance by 100 the pin and slot connections D. It will be noted that the section C is interiorly provided with the ribs E and thereby grooved to correspond to the remainder of the magazine, in such manner that when it occupies 105 its normal position (see Fig. 3), its ribs E are located between the adjacent magazine grooves, and the grooves A¹ are therefore substantially continuous and permit the unimpeded passage of the matrix ears X¹ 110

therethrough. If it be desired to remove the magazine, in order to replace it or for other reasons, the section C is shifted laterally (see Fig. 4) in such manner that the 5 continuity of the grooves is broken, and the ribs E are moved beneath the ears X¹ of the lowermost matrices. In this condition the matrices are locked in position and held securely against displacement, so that 10 the magazine may be freely handled without the danger of their being spilled therefrom.

As previously stated, I have shown my invention only in preferred form and by way of illustration, and in a special mode of 15 adaptation. Obviously, however, many variations and modifications thereof will suggest themselves to those skilled in the art without departure from its scope.

Having thus described my invention, its 20 construction and mode of operation, what I claim and desire to secure by Letters Patent of the United States is, as follows:

1. In a typographical machine, comprising type or matrices each formed at its upper end and on its opposite edges with projecting ears, the combination of a magazine to contain the type or matrices and comprising side plates formed on their inner faces with ribs to provide opposing sets of grooves 25 30 wherein the ears of the type or matrices

travel, and escapements projecting into the magazine through one of its side plates and adapted to engage the ears of the type or matrices on one of their edges, the other side plate of the magazine being formed with a section 35 movably arranged so as to set its ribs in front of the projecting ears on the opposite edges of the type or matrices and thus lock them therein.

2. In a typographical machine, the combination of a magazine to contain type or matrices, and comprising top and bottom plates formed on their adjacent faces with opposing grooves wherein the ears of the type or matrices travel, and escapements 40 45 projecting into the magazine through its bottom plate to control the delivery of the type or matrices therefrom, the top plate of the magazine being formed in sections, one movable laterally in relation to another so as to shift their corresponding grooves into and out of registry and thus permit or prevent the delivery of the type or matrices, as required.

In testimony whereof I affix my signature 55 in presence of two witnesses.

MELVIN W. MOREHOUSE.
